UNITED STATES PATENT OFFICE.

MARTIN WANNAGAT, OF NEW YORK, N. Y.

IMPROVEMENT IN COMBINED COLLARS AND MUFFS.

Specification forming part of Letters Patent No. 125,862, dated April 16, 1872.

To all whom it may concern:

Be it known that I, MARTIN WANNAGAT, of the city, county, and State of New York, have invented a new and useful Improvement in Combined Collar and Muff; and I do hereby declare the following to be a full, clear, and exact description thereof, which will enable those skilled in the art to make and use the same, reference being had to the accompanying drawing forming part of this specification, in which drawing—

Figure 1 is a front view of my invention. Fig. 2 is a cross-section in the line xx of Fig. 1.

Similar letters indicate corresponding parts.

This invention relates to a combination of a collar and muff; and consists of a collar of fur provided on the under side near or at its ends with suitable fastening devices for attachment to the outside of a muff, which is also provided at the proper places with corresponding fastening devices, in such a manner that the ends of the collar can be separately fastened to the muff. The muff is provided with a flap or curtain, which rises at or near the line where the ends of the collar are fastened, so that the curtain seems to be the prolongation of the collar. This combination not only produces an agreeable appearance, retaining the ends of the collar in front and close to the muff; but, also, supports the muff independently of the hands of the wearer, the muff being so connected to the collar that it is prevented from falling to the ground at such times as the wearer's hands are withdrawn from it. Moreover, the fastening devices are so made and arranged that they can be undone, and the two articles separated from each other to be worn apart.

The letter A designates a fur collar to be

worn around the neck, on whose lapels B B at or near their ends, are arranged hooks C, or other suitable fastening devices, one of which is seen in section in Fig. 2. One or more of such fastening devices are placed on each lapel of the collar according to its width. The letter D designates a muff, on the outer face of which, at corresponding points to meet the fastening devices on the collar, are arranged clasps E, or other suitable fastening devices to receive the hooks of the collar. The fastening devices E are secured to the pelt, and are hid by the fur of the muff, so that they are not exposed to view when the fastenings are undone and the muff is worn separate. The front of the muff is provided with a curtain of fur, F, which rises at or near the line where the ends of the collar are connected to the muff, and being of similar material, presents the appearance of being the terminal prolongation of the collar. The curtain serves also to cover a pocket, G, made in the muff and opening from the outside thereof.

I do not claim attaching to each end of a cape or collar separate cuffs, the sides of which when united form a muff, as such is not new; but

What I claim as new, and desire to secure by Letters Patent, is—

As a new article of manufacture, a combined collar and muff, detachably connected together by hooks and clasps, and provided with a flap, E, at their junction, substantially as and for the purpose set forth.

MARTIN WANNAGAT.
